UNITED STATES PATENT OFFICE

RUDOLF ETZKORN, OF OBERBRUCH REGIERUNGSBEZIRK AACHEN, GERMANY, AS-
SIGNOR TO AMERICAN GLANZSTOFF CORPORATION, OF NEW YORK, N. Y., A COR-
PORATION OF DELAWARE

SPOOL OR CYLINDER FOR USE IN THE WET HANDLING OF FRESHLY-SPUN FILAMENTS

Application filed November 19, 1930, Serial No. 496,715, and in Germany December 6, 1929.

The wet handling of freshly spun artificial filaments may be accomplished in many ways. Usually the filaments are wound upon spools or cylinders, and these spools or cylinders, as used in the art, may be solid-surfaced, perforated, or of porous material. Other spools and cylinders used in the art are provided with undulating projections on their surfaces, or with a porous textile coating, etc.

The present invention has for its object a new surface for spools and cylinders whereby new and useful results may be obtained.

One advantage of this new surface is that the filaments wound upon the spools or cylinders are more uniformly supported than when projections alone are used.

Other advantages will appear from a perusal of the following specifications and of the drawing, in which.

Figure 1 discloses a cross-section of a portion of a spool or cylinder surface;

Figure 2 a plan view of the same; and

Figure 3 a general plan view of a cylinder or spool.

In Figure 1, depressions "1" on the surface "2" of a spool, are shown. Figure 2 shows the manner in which the grooves "1" may be arranged so that rhombic-shaped figures "3" are formed on the face of the spool. These rhombuses are enclosed or defined by the grooves "1". Certain of the grooves, here indicated as "1", are arranged in such a relationship with respect to the intersecting grooves "1", that the rhombic-shaped figures are in staggered relation one to the other. The different planes of the rhombuses are thereby transposed so that no single peripheral groove is continuous. As the filaments are wound peripherally this arrangement prevents any of the filaments from lying entirely within one of the grooves "1". In Figure 3 I have shown the appearance of a porous cylinder provided with my newly-devised surface.

It has been discovered that such an arrangement materially reduces the time required for the ordinary steps of wet-handling filaments. These steps are the washing, desulfurizing, bleaching, etc. By my new arrangement the surface of the spool or cylinder is divided into a number of small, level planes which do not directly touch one another. It is better if the cross-sections of the grooves are so arranged that the filaments or threads rest upon surfaces having only small interstices.

The shaping of the spool surface has no relationship whatever with, and is therefore independent of, the material of which the spools are constructed. They may, for example, be made of metal, glass, earthenware, etc.

Compared with impermeable spools with porous coatings, for instance, those possessing textile coverings, my new spool has the advantageous distinction in that no obstruction of the grooves may occur. Textile coverings usually act as a filter and absorb small particles rinsed from the yarn by the liquids used in the wet-treatment process.

As there is no need to free a textile or porous coating from absorbed particles, etc., the period of treatment is further shortened.

As an example, it has been found that the time for washing freshly-spun viscose yarn may be reduced by from one-third to one-half through the use of my spool. This entails a considerable saving of liquid and time, and further provides for a more careful treatment of the yarn.

Similar advantageous results may be obtained in the other wet-handling processes, such as desulfurizing, acidifying, bleaching, etc.

I do not wish to be limited to the grooves as shown and described, since the plane surfaces may for example have the shape of rhombuses, squares or oblongs. They might also be formed as circles, ellipses or dumb-

belts. The rhombuses, etc., may be so situated that the grooves "1" partly meet.

Having now described my invention, as required by the patent statutes, what I claim

5 is:

1. A spool, the winding surface of which is provided with two series of grooves running in straight lines, the first series of grooves intersecting the second, but the 10 grooves of the second series being noncontinuous.

2. A spool having a winding surface adapted for use in the wet-handling of freshly-spun filaments, the solid surface of which 15 comprises a series of like planes in staggered relation one to the other, said planes being defined by intersecting sets of grooves, one of said sets being noncontinuous.

3. In a device of the class described, a 20 spool surface, grooves running longitudinally thereof, shorter grooves running from one of the first-mentioned grooves to another parallel therewith, said shorter grooves being noncontinuous, in their entirety, beyond 25 the distance between said two adjacent longitudinal grooves.

In testimony whereof I affix my signature.

RUDOLF ETZKORN.
